Primary Examiner — Jennifer L Watkins(74) Attorney, Agent, or Firm — Stetina Brunda Garred and Brucker(57) CLAIM

The ornamental design for a sock, as shown and described.

DESCRIPTION

FIG. 1 is a top plan view of a sock of the present invention showing my new design;

FIG. 2 is a right side elevational view thereof;

FIG. 3 is a front view thereof;

FIG. 4 is a bottom plan view thereof;

FIG. 5 is a left side view thereof; and,

FIG. 6 is a rear elevational view thereof.

The broken lines showing a human foot are for the purpose of depicting environment. All other broken lines depict stitching and portions of the sock and form no part of the claim.
